Primary Examiner — Cynthia R Underwood

(57) **CLAIM**

The ornamental design for a fabric computer case, as shown and described.

DESCRIPTION

FIG. 1 is a first perspective view of a fabric computer case showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the fabric computer case thereof;

FIG. 10 is an opening state of the fabric computer case thereof; and,

FIG. 11 is an enlarged view of the selected portion 11 in FIG. 2.

The broken lines shown in the drawings depict portions of the fabric computer case that form no part of the claim. The broken lines encircling the enlarged portion in FIGS. 2 and 11 are not part of the claim.

1 Claim, 11 Drawing Sheets
